United States Patent Office

Des. 183,888
Patented Nov. 11, 1958

183,888

CLOCK OR SIMILAR ARTICLE

William V. Judson, Dover, Mass., assignor to General
Electric Company, a corporation of New York

Application October 1, 1957, Serial No. 47,935

Term of patent 3½ years

(Cl. D42—7)

Des. 183,888

PAGE 2

Fig. 3.

Fig. 4.

Fig. 5.

Fig. 6.

Fig. 1 is a front perspective view of a clock embodying my new design;

Fig. 2 is a side elevational view of the clock shown in Fig. 1;

Fig. 3 is a front elevational view of the clock shown in Fig. 1;

Fig. 4 is a top plan view of the clock shown in Fig. 1;

Fig. 5 is a rear elevational view of the clock shown in Fig. 1; and

Fig. 6 is a bottom plan view of the clock shown in Fig. 1.

I claim:

The ornamental design for a clock or similar article, substantially as shown.
